UNITED STATES PATENT OFFICE.

HARRY C. BUHOUP, OF CHICAGO, ILLINOIS, ASSIGNOR TO WILLIAM McCONWAY, OF PITTSBURG, PENNSYLVANIA.

CAR-BUFFING MECHANISM.

SPECIFICATION forming part of Letters Patent No. 517,378, dated March 27, 1894.

Application filed April 24, 1893. Serial No. 471,598. (No model.)

To all whom it may concern:

Be it known that I, HARRY C. BUHOUP, a citizen of the United States, residing at Chicago, in the county of Cook and State of Illinois, 5 have invented or discovered certain new and useful Improvements in Car-Buffing Mechanism, of which improvements the following is a specification.

The invention described herein relates to 10 certain improvements in car coupling and buffing mechanism, and has for its object a connection from the coupling mechanism at one end of a car to the buffing mechanism at the opposite end of the car, so arranged that 15 an inward or outward movement of the coupling mechanism will effect an outward movement of the buffing mechanism, for the purpose of reducing the independent to and fro movements of the cars in a train.

20 In general terms, the invention consists in the construction and combination substantially as hereinafter more fully described and claimed.

In the accompanying drawings forming a 25 part of this specification, Figure 1 is an inverted plan view of the draft and buffing mechanism of a car, embodying my improvement. Figs. 2, 3 and 4 are sectional detail views illustrating certain modifications.

30 In the practice of my invention, the coupling mechanisms are of the Janney or any other suitable type or construction, consisting of the couplers 1, 1^a, the draft springs 2, 2^a, and follower plates 3, 3^a, the springs and 35 follower plates being arranged with straps or spring-pockets 4, 4^a, connected to the barrel of the coupler by bolts 5, 5^a. The buffing mechanisms consist of the stems 6, 6^a projecting through the end sills of the car, face plates 7, 7^a, equalizing levers 8, 8^a, loosely connected to the rear ends of the stems and 40 springs 9, 9^a, surrounding the stems and interposed between the equalizing levers and shoulders on the stems.

45 The upper ends of levers 10, 10^a, which are pivotally mounted on pins 11, 11^a, supported by the center sills of the car, are connected to the equalizing levers 8, 8^a, at points about midway of their length. These levers extend 50 down around the coupler barrels as shown in Fig. 1, or through slots in the same as shown

in Figs. 2, 3 and 4, and have their lower ends connected to the tail pins or bolts 5, 5^a, by eye bolts 19, 19^a and to levers 12, 12^a, at points intermediate of their ends. These levers 12, 55 12^a, have one end pivoted to one of the center sills of the car, while the other ends are connected by rods 13, 13^a, to one end of the floating levers 14 and 14^a, which are arranged transversely of the car, and pass through slots 50 or between lugs 15 on the bolts 16, 16^a, connected at their front ends to the couplers, so as to move back and forth therewith. Fulcrum pins 17, 18, and 17^a, 18^a, are secured on the center sills or other portion of the car, on 65 opposite sides of the floating levers. It will be observed that the floating lever 14, forming one of the connections of the buffing mechanism at one end of the car is connected to and operated by the bolt 16^a of the coupler 1^a, at 70 the opposite end of the car. As the couplers are pulled out, the levers 14 and 14^a are shifted through the medium of the bolts 16, 16^a. During this movement of the couplers and floating levers, the pins 17 and 17^a serve as 75 fulcrums, and, hence, the floating levers exert a pull on the rods 13 and 13^a, and so shift the levers 12, 12^a and yoke levers 10, 10^a, as to push the equalizing levers 8, 8^a, and the buffing stems and plates outwardly. As the couplers 80 are forced inward, the floating levers are similarly shifted, the pins 18, 18^a serve as fulcrums, but this movement of the floating levers also imparts a pull on the rods 13, 13^a, thereby shifting the buffing stems and plates out- 85 wardly.

It will be observed that whether the couplers are moved out or in, the movement of the buffing mechanism is always out, the floating levers, when the couplers are pulled out, operating as levers of the third class, while they 90 operate as levers of the first class, when the couplers are moved in. The connection between the yoke lever and the tail pins or bolts is such that when the coupler at one end 95 is forced in, the yoke lever will be so shifted as to cause an outward movement of the buffer plate at the same end. As hereinbefore stated, both buffer plates can be caused to move outwardly by the inward movement of 100 one of the coupling mechanisms, the movement of the buffing mechanism at the same

end as the coupler being transmitted from the coupler to the opposite end of the car and then returned to the buffing mechanism by the system of levers hereinbefore described.

5 As shown in Fig. 3 only one central buffing stem and plate may be employed, in which case the equalizing lever is omitted.

I claim herein as my invention—

1. The combination of a buffing mechanism 10 arranged at one end of a car, a coupling mechanism arranged at the opposite end of the car, and connections interposed between said mechanisms, whereby a longitudinal movement of the coupling mechanism either in or 15 out will shift the buffing mechanism outwardly, substantially as set forth.

2. The combination of a buffing mechanism arranged at one end of a car, a coupling mechanism arranged at the opposite end of the car, 20 and a system of levers connecting said mechanisms, whereby the coupling mechanism when shifted longitudinally either in or out will shift the buffing mechanism outwardly, substantially as set forth.

25 3. The combination of a buffing mechanism arranged at one end of a car, a coupling mechanism arranged at the opposite end of the car, a floating lever having two fulcra, and con-

nected to the buffing and coupling mechanisms, whereby said lever is adapted to effect 30 an outward movement of the buffing mechanism, when shifted either in or out by the coupling mechanism, substantially as set forth.

4. The combination of a coupling mechanism arranged at one end of a car, a lever movable in and out with the coupling mechanism and having two fulcra, a connection from said lever to a lever at the opposite end of the car, and a buffing mechanism operated by the latter lever, whereby a movement in or out of 40 the coupling mechanism will force the buffer outwardly, substantially as set forth.

5. The combination of a coupling mechanism at one end of the car, a buffing mechanism at each end of the car, connections 45 between the buffing mechanisms and the coupling mechanism, whereby a movement in or out of the coupling mechanism will force both buffing mechanisms outwardly, substantially 50 as set forth.

In testimony whereof I have hereunto set my hand.

HARRY C. BUHOUP.
